SPRING CATCH

Horace H. Raymond, Berlin, Conn., assignor to
The Stanley Works, New Britain, Conn., a
corporation of Connecticut

Application January 9, 1937, Serial No. 119,789

3 Claims. (Cl. 292—223)

This invention relates to a spring catch and, more particularly, to a spring catch adapted to secure refrigerator doors and other closures.

It is an aim of the present invention to provide a spring catch of the type described having various features of novelty and advantage and which is particularly characterized by its extreme simplicity in construction, economy in manufacture, and ease and facility with which the parts may be assembled as well as its strength and durability and the facility with which it may be operated.

It is a further object to provide a spring catch having a minimum number of parts, most of which may be formed from sheet metal bent to shape.

It is a still further object of my invention to provide a spring catch which may be easily operated and wherein the parts are prevented from rattling.

A still further object of the invention is to provide an improved handle of exceedingly economical construction and of very pleasing appearance.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the accompanying drawings:

Figure 1 is a side elevation of my catch showing it applied to a refrigerator door to secure it in position;

Fig. 2 is a plan view of my catch in latched position;

Fig. 3 is a longitudinal section along line 3—3 of Fig. 2 and showing the catch in opened position;

Fig. 4 is a fragmentary view of the catch taken substantially along line 4—4 of Fig. 1;

Fig. 5 is a sectional view through line 5—5 of Fig. 1; and

Fig. 6 is a perspective view of the operating handle in my invention.

Referring to the accompanying drawings illustrating one embodiment of the present invention, I have shown my catch A applied to a swinging closure such as a refrigerator door B movable relative to a suitable door casing C and into and out of latched engagement with a keeper D secured to the door casing. It will, of course, be evident that this invention is applicable to

any similar use, and it is not desired that it be limited to the present showing.

The catch embodies a main frame or casing 10 blanked out and bent to form from sheet metal and having substantially parallel spaced side walls 11 interconnected by a top wall 13. The bottoms of the side walls extend outwardly to form supporting flanges 14 having spaced holes therethrough adapted to receive securing means such as screws 15. An operating handle 16, blanked out from sheet metal and bent to form, has a base 17 from the opposed edges of which extend outwardly projecting spaced arms 18. In the present showing, these arms are longitudinally curved at their opposite ends and are cut away from base 17 intermediate of their ends, as at 19, to provide a convenient hand grip for the handle. Top wall 13 is cut away, as at 20, to provide a slot open at its rearward end, and a pair of opposed flange portions 20' forming portions 20 of wall 13 extend substantially throughout the length of the slot and to either side thereof.

The base 17 has a rearwardly extending lip which is bent downwardly and curled back upon itself to form a sleeve 17' located within the rearward open end of slot 20 and journaled upon a transverse pin 22 secured within the side walls 11, as by riveting. Pin 22 is preferably so located that when the handle is in a closed position (Fig. 1), base 17 will lie flat against wall 13. The inner curled end of the lip terminates in a short tongue 17'' located intermediate of walls 11. A coiled spring 23, loosely mounted on pin 22 within one end of sleeve 17' and between tongue 17'' and a side wall, has one end 23' resiliently engaging a shoulder portion 17a of sleeve 17' and the other end 23'' resiliently engaging the under side of a flange 20' adjacent to wall 11, thus urging handle 16 to a closed position in contact with the casing.

The forward ends of side walls 11 have correspondingly depending portions 25 adapted to overlie the edge of door B and to receive a pivotally mounted latch member 26 therebetween. In the present instance, latch 26 is bent to form from a blanked out sheet of metal and is provided with a forwardly extending nose 27 and opposed side walls 28 journaled at their lower ends upon a transversely extending pin 29 secured within depending portions 25. The side walls 28 are interconnected by a camming face 27' which is bent back at its upper end from nose 27 to form a lacking face 27'' of arcuate contour. Side walls 28 also terminate at their upper ends in a corresponding arcuate contour to form a continua-

tion of face 27". A coiled spring 30 loosely mounted upon pin 29 between walls 28 has one end 30' resiliently engaging the latch and its other end 30" resiliently engaging a transversely extending pin 31 mounted within side walls 11 somewhat above pin 29 and resiliently tending to urge nose 27 to a forward operative position, as shown in Fig. 1. In the present showing, spring 30 is illustrated as having a pair of spaced 10 coils interconnected by an intermediate projecting U-shaped end 30" engaging pin 31, and each of the coils has an outwardly projecting end 30' engaging the latch. However, it will be evident that the same result could be accomplished with 15 a spring having a continuous coil and a projection at each end.

A plate 35 is mounted in depending relation beneath the base 17 and within slot 20 to operatively engage a bail 37 secured to latch 26. Plate 20 35 may be blanked out from sheet metal, and, as herein shown, is provided with two upwardly extending spaced studs 38 received within correspondingly located apertures in base 17 and headed over to fasten the plate in position. 25 Plate 35 has a rearwardly extending tongue 35' provided with a top face 39 in spaced relation to the bottom of base 17 and terminating at its forward end in a shoulder 39". Bail 37 may comprise a wire of U or hairpin shape having outward turned forward ends journalled, as at 41, in the upper ends of walls 28 of latch 26. The rearward end of the bail 37 terminates in a loop 42 straddling tongue 35' and slidably mounted on surface 39 beneath base 17. Spring 30 normally 30 urges the latch member forwardly to a latching position (Fig. 1), and the extreme forward movement of this latch member is limited by the engagement of loop 42 with shoulder 39". The rearward movement of the latch member and 35 the operative movement of handle 16 is limited by the latch member abutting against pin 31, as shown in Fig. 3.

Keeper D which is preferably blanked out from sheet metal and bent to form is provided 40 with spaced side walls 44 interconnected by a curved end wall 45 and terminating at their respective lower ends in outwardly projecting flanges 46 having holes therethrough to receive suitable securing means such as screws 47 for mounting the keeper on a casing C in proper 45 relation to latch member 26. The upper portion of end wall 45 is preferably provided with an extended lip which is curled back upon itself between side walls 44, as at 50, to engage locking face 27' of latch member 26 in camming relation 50 so that the spring catch will resiliently snap into position when the door is pushed shut.

In the operation of my device, handle 16 is 55 swung outwardly from casing 10 and shoulder 39' engages loop 42 causing latch 26 to be withdrawn from keeper engagement and into the casing from the position shown in Fig. 1 to the position shown in Fig. 3. Further pulling upon the handle at this time serves to open the door 60 B. Upon release of the handle, springs 23 and 30 cooperate to return the handle and latch members to closed positions. Upon pushing the

door shut, lip 50 cams face 27' and nose 27 towards casing 10, after which spring 30 quickly snaps the latch member into camming engagement beneath lip 50 to the position shown in Fig. 1, thus maintaining the door in latched position. It will be appreciated that as the latch member 26 is cammed into position, loop 42 is free to slide rearwardly along surface 39. Hence, the door may be pushed to a latched position without requiring any operative movement of handle 16.

As many changes could be made in the above construction and many apparently widely different embodiments of this invention could be made without departing from the scope thereof, 15 it is intended that all matter contained in the above description or shown in the accompanying drawings shall be interpreted as illustrative and not in a limiting sense.

It is also to be understood that the language 20 used in the following claims is intended to cover all of the generic and specific features of the invention herein described and all statements of the scope of the invention which, as a matter of language, might be said to fall therebetween. 25

I claim as my invention:

1. A spring catch comprising a casing, a latch member pivotally supported in the forward end of said casing for movement into and out of latching position, means urging the latch member to a latching position, a handle pivotally connected to the rear end of said casing and normally extending forwardly and overlying said casing, means urging the handle towards the casing, said handle having between its ends a plate 30 extending into said casing and forming a slot with an abutment at its forward end, and a U-shaped wire bail operatively connecting said latch member to said plate, said bail having outward turned forward ends journalled in openings in 35 said latch member, the closed end of said bail being arranged to operate in said slot and to engage said abutment.

2. In a spring catch, a one piece sheet metal handle comprising an elongated base portion on the handle, and longitudinally curved arms projecting outwardly from the opposite side edges of the base portion in parallel spaced relation and at right angles to the general plane of said base portion.

3. A spring catch comprising a casing having 50 a rearwardly disposed opening in the top thereof, a latch member pivotally supported in the forward end of said casing for movement into and out of latching position, a handle pivoted to the rear end of said casing for swinging movement into and out of overlying relation to said casing and opening, and a wire connecting member having one end pivotally connected to said latch member and having its free end loosely connected 55 to said handle adjacent the pivot of the latter, said wire normally lying within the casing whereby when the handle is swung away from said casing the free end of said wire may be moved upwardly through said opening to withdraw said latch member out of latching position. 60

HORACE H. RAYMOND.
